UNITED STATES PATENT OFFICE.

JOSEF KRYSZTOFIAK, OF NEW YORK, N. Y., ASSIGNOR, BY DIRECT AND MESNE ASSIGNMENTS, TO L'AUREOLE CO., INC., OF NEW YORK, N. Y., A CORPORATION OF NEW YORK.

HAIR-CURLING DEVICE.

Application filed March 22, 1923. Serial No. 626,951.

To all whom it may concern:

Be it known that I, JOSEF KRYSZTOFIAK, a citizen of the Republic of Poland, and residing at 4174 Park Avenue, New York city, have invented certain new and useful Improvements in Hair-Curling Devices, of which the following is a specification.

My invention relates to hair curling devices, popularly known as permanent wave curlers, and has for its object, means for effectively and conveniently forming curls in hair, of such size and form as may be desired, either by the process disclosed by me in Patent No. 1,440,163, issued December 26th, 1922, or by other methods applicable thereto.

One of the objects of my invention is to provide means whereby electric heat may be employed effectively for the purpose of forming curls in hair, the same being so regulated that there is more heat generated at one end of the device than at the other.

Another object of my invention lies in the means whereby the hair can be clamped and enclosed within the heater, with the greatest facility,—the clamp being controlled from the rear of the device, and away from the subject's scalp.

Another object of my invention lies in the means for preventing excessive heat reaching the scalp.

Another object of my invention lies in the concentric arrangement of the handles by which the device may be conveniently manipulated, while consuming a minimum space.

Referring to the drawings:

Fig. 1 shows a completely assembled view, partly in section, of my invention.

Fig. 2 is a sectional view of the same, looking at section 2—2, Fig. 1, from the right.

Fig. 3 is a sectional view of Fig. 1, at section 3—3, looking at the same from the left, broken away in one place to show the interior parts.

Fig. 4 is a view of Fig. 1, looking at the same from the right.

Fig. 5 is a perspective view of the heat insulating washer.

Fig. 6 is a detail part.

Fig. 7 is a detail.

Fig. 8 is a detail.

My curler consists of two essential parts,—the electric heating portion of the device with its handle for holding and manipulating the same, and the receptacle in which the hair is inserted and its parts.

The electric heater consists of a tube, 1, on one end of which is wound suitable heat resisting insulating material, 2, on which in turn is wound a layer of spaced coils, 3, of wires having a comparatively high resistance co-efficient. Over this layer of coils, 3, I wind a second layer of insulating material, 4. These layers of insulating material, 2 and 4, and the coils, 3, are wound substantially throughout the length of the heating section of the tube, 1. Upon these coils and insulation I wind additional coils, 5, 6 and 7, suitably insulated, as already explained in connection with coil, 3. The coils, 5, 6 and 7 do not run the entire length of the heating element as shown in Fig. 1. The coils, 5, run for three-quarters of the length, the coils, 6, run one-half of the length and the coils, 7, run one-quarter the length of the heating element. All of these coils, however, start substantially at the end of the heating element as shown. It is obvious that this arrangement produces more heat at one end than at the other of the heating element, and graduates to any degree desired, the amount of heat along the length of the element. It is understood, of course, that more heat is needed at one end of the heating element than at the other end, as there is more hair to heat at the end of the device, nearest the scalp.

Over the outside of the heating coils, 3, 5, 6 and 7, and their respective layers of insulation, I provide a covering, or envelope, 8, contracted at one end and preferably of tubular form, which, with the head, 9, and tube, 1, completely encloses the electric portion of my device.

In the head, 9, I provide bushings, 10, and 11, through which the leads running to the electric resistance coils pass. The tube, 1, extends beyond the end of the heating element, and at the extreme end, 12, is flanged, as shown. Next to the head, 9, I provide a heat insulating washer, 13, through which the bushings 10 and 11, referred to, also pass. Between the washer, 13, and the flange, 12,

I wind on the tube, 1, one or more layers of heavy twine best suited to stand the heat generated, and to thermally insulate the hands of the operator from the tube 1. The 5 opposite end of the tube, 1, to the windings, 14, I provide with lugs, 15, Fig. 7, extending a short distance from the end of the tube, the purpose of which will be hereinafter described.

10 That portion of the device in which the hair is inserted consists of a tube, 16, somewhat longer, but smaller in diameter, than the tube, 1. The tube, 16, is provided with a head, 17, having a concentric opening, 18, through which the end of the pencil, 19, passes. To assist the pencil, 19, to enter the opening, 18, I dish or cup the head, 17, as shown and I also round the end of the pencil, 19. To the end of the tube, 16, I 15 detachably secure a ring, 20, preferably made of heat insulating material, such as fibre, bakelite, etc., so as not to transmit the heat from the tube, 16, to the operator's fingers. I may secure this ring, 20, to the tube, 16, in 20 any suitable manner, such as by headless screws, 21. At the opposite end of the tube, 16, I form a flange, 22. This flange, 22, is provided with three holes, 23, spaced 20° apart. Pivoted in each of these holes, 23, I 25 provide iris members, 24, free to move in relation to the flange, 22. The opposite ends of the iris members, 24, are provided with extruded lugs, 28, engaging with holes, 26, in the disc, 25, see Fig. 6. The three holes, 30 26, in disc, 25, are elongated radially, as shown. I prefer to make the iris members three in number, and I also prefer to provide them with extruded parts at the ends, 27 and 28, to form pivotal and sliding bearings, 35 respectively, engaging with the round holes, 23, in the flange, 22, of the tube, 16, and the long holes, 26, in disc, 25. I may or may not head or rivet over the ends of the extrusions, 27 and 28. Enclosing the iris members, 40 just described, is a shell, 29, which engages with an enclosing head, 30, having openings, 31, Fig. 8, to receive the projections, 15, on tube, 1, referred to above, thereby detachably assembling the electrical unit portion 45 of my device to the hair receiving member. The ring, 20, prevents these parts from disengaging in operation.

In Fig. 1 I have shown the iris members, 24, the flange, 22, and shell, 29, with a curved 50 surface. I prefer to make the end of my curler in this way, but it works well also if made flat instead of curved. In Fig. 5 I have shown a heat insulating washer, 32, which I prefer to make of felt, and which I 55 apply between the scalp and the heater when in use. This washer, 32, is provided with a central opening, 33, through which the hair to be curled passes. The washer, 32, is provided with two overlapping sectors, 34 and 35, as shown in Fig. 5, so that the direct

heat of the electric unit cannot pass from my curler to the scalp.

The operation of my device will now be readily understood. The hair to be curled is twisted and then wound upon the pencil, 19, 70 and secured thereto, at the ends of the pencil, 19, at 36 and 37. The heat insulating washer, 32, is placed between the scalp and the pencil. Surrounding the hair to be curled, and which has been wound upon the pencil, I provide a covering, 39, of fabric or other suitable material with which I can apply any desired solution for treating the hair as already disclosed in my above referred to Letters Patent. This covering I 80 prefer to make of felt or flannel saturated with the desired solutions. It is obvious, however, that my device is equally applicable for use where no such covering or solutions are used, or where altogether different methods 85 from those disclosed in my above mentioned Letters Patent are employed. The pencil with the hair on it is slipped into the heating element. After the hair has been inserted into the heating element, the operator rotates the tubes, 1 and 16, with reference to each other. This action causes the iris opening, 38, to close down upon the hair next to the heat insulating washer, 32, near the scalp, thereby securing the hair in place in 90 the heating element, and at the same time, to a large extent, preventing the escape of steam from the tube, 16, to impinge upon the scalp. The insulating washer, 32, gives an additional factor of safety in this respect. The hair is then subjected to the heat of the element until the process is completed. In thus describing the method of operation I have purposely not referred to the treatment whereby the hair is subjected to the various solutions employed, as this is fully disclosed in my above referred to Letters Patent, No. 1,440,163. 105

Having described my invention, what I claim and wish to have secured by Letters 110 Patent is:

1. A hair curler, comprising a heated receptacle to receive the hair, an electric heater for the same, clamping means secured at one end of the receptacle, adapted to secure the hair therein, and means at the opposite end of the receptacle to operate the clamping means to secure or release the hair in the receptacle. 115

2. A hair curler, comprising a tubular receptacle to receive the hair, an electric unit surrounding one end of the receptacle, a heat insulated handle at the other end of the receptacle, and a clamp secured to the receptacle, adapted to secure the hair to be 120 curled therein.

3. In a hair curler, a tubular receptacle for the hair, a clamp for the hair, forming an enclosure for one end of the receptacle, comprising a plurality of pivoted means 125

forming an iris opening, and means at the opposite end of the receptacle adapted to control the size of said clamping opening.

4. In a hair curler, a tubular heating receptacle for the hair to be curled, a permanent enclosure for one end of the hair, and an adjustable enclosure for the opposite end, forming a clamp adapted to secure the hair in the receptacle, and means controlling the clamp at the permanent enclosure.

5. In a hair curler, a receptacle for the hair, comprising a pair of tubes, one tube inserted within the other, and an adjustable clamp for the hair, secured to both tubes, said tubes adapted to control the operation of the clamp by the rotation of one tube in the other.

6. In a hair curler, a tubular receptacle for the hair, having an adjustable concentric clamp for the hair to be curled, securing the

hair to be curled therein, and means adapted to change the size of the clamp, while maintaining it concentric with the receptacle.

7. An electric hair curling device, comprising a tubular body, an electric unit wound on one end thereof, a handle formed by the opposite end of body, a second tubular body in the first named body, free to rotate therein, means at the end of the second tubular body for rotating it within the first named body, and an adjustable clamp for securing the hair at the opposite end, and adapted to be opened and closed by the relative movement of the two tubular bodies.

In testimony whereof I affix my signature in the presence of a witness.

JOSEF KRYSZTOFIAK.
